UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,384,156.

Specification of Letters Patent. Patented July 12, 1921.

Application filed May 14, 1920. Serial No. 381,319.

To all whom it may concern:

Be it known that I, EDWARD R. SARGENT, a citizen of the United States, and a resident of the city of New Haven, State of Connecticut, have invented certain new and useful Improvements in Casket-Handles, of which the following is a full, clear, and exact description.

My invention relates to casket handles, 10 and especially to those types of handles wherein the handle bar is held in arms pivotally mounted on the side of the casket.

The invention also has special reference 15 to casket handles wherein the arms pivotally mounted upon the side of the casket are made of soft metal.

One object of this invention is to provide 20 an improved means for securing the handle bars of a casket handle to the pivoted arms thereof.

Another object of this invention is to provide 25 a strengthening brace for the pivoted arms of a casket handle, of improved character.

25 A still further object of this invention is to provide a strengthening brace in an arm of this character which will be capable of being used with handle bars of various diameters.

30 To these and other ends, the invention consists in the novel features and combinations of parts to be hereinafter described and claimed.

Figure 1 is a front elevation of a casket 35 handle, embodying my inventions, the socket plates being omitted;

Fig. 2 is an enlarged rear elevational 40 view of one of the ends of the handle showing the mounting of the bar in the arm and tip;

Fig. 3 is a view similar to Fig. 2, but showing a slightly different form of mounting used with a bar of smaller diameter;

Fig. 4 is a perspective view of my im- 45 proved brace; and

Fig. 5 is a view similar to Figs. 2 and 3, but showing a still different form of mounting.

While in the accompanying drawings I 50 have shown my invention as applied to casket handles wherein the handle bar is of circular cross section, and wherein the arm and tip are cast in one piece, it will be un-

derstood that certain features and improvements are equally applicable to other types 55 of bars and handles, and I do not desire to be restricted to the exact form shown.

In the embodiment of my invention illustrated by the accompanying drawings, I have shown in Fig. 1 a casket handle comprising the usual handle bar 10, circular in cross section, and the usual arms 11 and ornamental tips 12. The arms 11 and tips 12 are, in practice, made of soft metal, while the bars 10 are, in their usual form, of tube 60 or bar construction. The material of which the parts are made, however, may be varied without affecting the merits or the principle of the invention described herein.

As the soft metal of which the arms are 70 made is expensive and is not possessed of great strength, it is usual to dispense with some of this metal at the rear of the arm and to provide a brace of hard metal to give the arm the necessary rigidity. With my 75 improved brace and fastening means, I am enabled to dispense with practically all of the soft metal on the rear half of the arm and still secure the bar firmly in place.

I have provided the arms 11 with a brace 80 member 14 of hard metal, which consists of an upper shank portion 15 and a lower broadened portion 16, provided with an opening 17, circular in shape, in the form shown to conform to the shape of the handle bar 10. In Figs. 2, 3 and 4, this brace is shown as provided with oppositely positioned lugs 18 on the lower portion 16 of the arm, through one of which a screw or nail 19 is adapted to be inserted to secure 90 the bar against movement within the handle. It is to be noted that only one of these lugs is to be used at a time, but the two are provided that the same brace member may be used on either the right or the left end of 95 the handle. For the same purpose both sides of the shank portion 15 of the brace are substantially identical in shape, thus rendering the entire brace symmetrical in shape with respect to a central longitudinal line. 100

As shown in Figs. 2, 3 and 5, the soft metal arm is cast about the brace 14, in such a shape as to leave a bore or opening for the reception of the bar. In Fig. 3, the brace 14 is generally centrally disposed longitudinally of this bore 20, and the bar 10 is in-

serted in this bore, passing through the ring opening 17, until the end abuts the tip 12. The screw 19 is then passed through the opening in the exposed lug 18 and into the 5 bar 10.

An important advantage of my brace construction is that the same brace may be used with handle bars of various sizes. If, for instance, the opening 17 will snugly receive 10 a three-quarter inch bar and it is desired to use a seven-eighth bar which is too large to enter the opening, the brace is reversed so that the lugs 18 extend toward the tip of the handle, as shown in Fig. 2. The arm 10 is 15 then inserted and instead of passing through the opening 17, the edge of the bar abuts the border 16 of this opening. The screw 19 is then inserted through the lug 18 and through a wooden bar 23 usually provided 20 within the bar 10'. The bore in this arm is shown as of different diameters on the opposite sides of the brace 14, the outer bore 21, being of a diameter to receive a large bar 10', while the inner bore 22 is designed to 25 receive a smaller bar, which would pass through the opening 17 in the brace. It is thus seen that the same brace, without being varied in any of its proportions, may not only be used for right and left arms, but 30 also be used for bars of different diameters, in fact any diameter that will pass within the bores 20 or 21. Those bars that will not pass through between the lugs 18 and through the opening 17, will abut against the 35 ring portion 16, and the lug screwed to the inner wooden bar 23.

In Fig. 5, I have shown an arm 11, having a bore 24 which is shaped to fit the end of the arm adjacent the tip 12. When the bar 10 40 is firmly pressed into this properly shaped bore of soft metal, it will be lodged therein so that no securing means such as the lug and screw shown in the other forms are needed. The wooden inner bar 23 may also 45 be dispensed with in this form. The braces 14 shown in this figure may also be used at the right or left end of the handle, or, if desired, this bore may be used when the lug 18 is provided and bars of different sizes 50 used, other than those which would just snugly fit the bore.

While I have shown my invention applied to a casket handle having the arm and tip thereof cast in a single piece, it is to be 55 understood that it is not limited to use with this particular type of handle but may also be used with a handle of the form shown in my prior Patent No. 1,164,220, granted December 14, 1915, where the tip is separate 60 from the arm.

It will be apparent that the invention is capable of other embodiments and modifications without departing from the spirit thereof or from the scope of the appended 65 claims.

What I claim is:

1. In a casket handle, an arm, a brace therefor, and a handle bar connected thereto, said brace being adapted to be used in reversed positions with an arm at either end 70 of bar.

2. In a casket handle, a handle bar, an arm at each end thereof, a brace for each of said arms, said braces being identical, but in reversed positions. 75

3. In a casket handle, a handle bar, a supporting arm therefor, a brace for said arm provided with an opening for the reception of said bar, said brace being adapted for use in reversed positions at the right or left 80 end of said bar.

4. In a casket handle, a handle bar, a supporting arm therefor, a brace for said arm provided with an opening for the reception of said bar, and means on said brace 85 adapting it for use in reversed positions with the arm at either end of said bar.

5. In a casket handle, a supporting arm, a brace therefor, said brace being adapted to be associated with said arm in reversed positions. 90

6. In a casket handle, a handle bar, an arm having a bore for the reception of said bar, one end of said bore being of less diameter than the other. 95

7. In a casket handle, a supporting arm having a bore, said bore being divided transversely into sections of different diameters.

8. In a casket handle, a supporting arm having a bore, said bore being divided transversely into sections of different diameters, and a strengthening brace at said point of division. 100

9. In a casket handle, a supporting arm, having a bore, a strengthening brace therefor having an opening coinciding with said bore, said brace being situated in the soft metal of the supporting arm, the bore of the arm on one side of said brace being smaller in diameter than the bore on the other side. 110

10. In a casket handle, a handle bar supporting arm, and means to operatively connect said arm to handle bars of different sizes.

11. In a casket handle, a handle bar and a supporting arm provided with a strengthening brace, said arm and brace being adapted to be used with handle bars of different sectional areas. 115

12. In a casket handle, a handle bar, a supporting arm and a strengthening brace therefor, the front and rear portions of said brace being symmetrically shaped with respect to a central longitudinal line, so that it may be used with an arm at either end of the handle bar. 120

In witness whereof, I have hereunto set my hand on this 12th day of May, 1920.

EDWARD R. SARGENT.
